A. FROMHOLD.
METAL WINDOW CONSTRUCTION.
APPLICATION FILED AUG. 7, 1913.

1,096,295.

Patented May 12, 1914.

UNITED STATES PATENT OFFICE.

ALEXANDER FROMHOLD, OF RUTHERFORD, NEW JERSEY, ASSIGNOR TO S. H. POMEROY COMPANY, OF NEW YORK, N. Y., A CORPORATION OF NEW YORK.

METAL WINDOW CONSTRUCTION.

1,096,295.

Specification of Letters Patent.

Patented May 12, 1914.

Application filed August 7, 1913. Serial No. 783,480.

To all whom it may concern:

Be it known that I, ALEXANDER FROMHOLD, a citizen of the United States, residing in Rutherford, Bergen county, State of New Jersey, have invented certain new and useful Improvements in Metal Window Construction, of which the following is a specification, reference being had to the accompanying drawing, which forms a part hereof.

10 In the construction of double-hung windows of sheet metal, in which both sashes move up and down in the window frame one object to be kept specially in view is the rendering of the window weather-proof, that is, 15 the making of provision to prevent the entrance of air between the sashes and the frame. This has been accomplished effectively heretofore by the provision of an adjustable weather-guard which is formed independently of each sash and is secured adjustably thereto.

Such construction, however, involves additional expense and it is the object of this invention to provide a less expensive form 25 of construction which shall nevertheless be at least as effective as the former construction in preventing the entrance of air between each sash and the window.

In accordance with the invention the 30 pocket, or portion of the vertical window frame which is adjacent to the sashes, is so formed as to provide two guide channels for each sash and each sash is also formed so as to provide two guides to enter such channels, so that the admission of air is effectively prevented.

The invention will be more fully explained hereinafter with reference to the accompanying drawing in which it is illustrated and in which—

Figure 1 is a view in outside elevation of a window, including frame and sashes, which embodies the invention. Fig. 2 is a view, on an enlarged scale partly broken out 45 to save space, in section on the vertical plane indicated by the broken line 2—2 of Fig. 1, looking in the direction of the arrows. Fig. 3 is a detail view, also on an enlarged scale, in section on the plane indicated by the line 50 3—3 of Fig. 1, looking in the direction of the arrows.

The head *a*, sill *b* and the vertical side bars *c* of the window frame are constructed of sheet metal in substantially the same manner as heretofore, except with respect to the

face *d* or pocket, as it is called in the art, of each vertical side bar. Each vertical side bar *c* of the frame, is formed of a continuous sheet of metal, having near the outer and inner sides inturned flanges *c*¹, between and 60 upon which is fitted a pocket *d*, which may be secured in place by heavy metal braces *e*, which are secured at their ends to the vertical side bar, as by screws *e*¹, and are secured to the pocket as by screws *e*². The 65 pocket *d*, or facing of the side frame, is made of a single sheet of metal which is bent, as at *d*¹ to lap the flanges *c*¹ and to form, adjacent to the flanges *c*¹, guide channels *d*². It is also bent to form intermediate 70 guide channels *d*³. There are thus provided in the facing or pocket four vertical guide channels *d*² and *d*³, two for each sash.

A double-hung window, such as that to which this invention relates, comprises two 75 vertically movable sashes, an upper sash *f* and a lower sash *g*. Each of these sashes is made of sheet metal. The head *f*¹ and the meeting rail *f*² of the upper sash and the foot *g*¹ and the meeting rail *g*² of the lower 80 sash may be formed in any suitable manner in harmony with the construction of the side bars, with which the invention is particularly concerned. Each side bar *h* is made of a continuous sheet of metal bent to 85 form a front face *h*¹ with a recess *h*² to receive the glass, parallel inner and outer faces *h*³ *h*⁴, a rear face *h*⁵ and guide ribs *h*⁶ *h*⁷ which project beyond the rear face *h*⁵ at each edge thereof. Each rib *h*⁶ is formed 90 bylapping one face *h*⁸ about a flange of the rear face *h*⁵, while each rib *h*⁷ is formed by doubling the metal upon itself, as clearly shown in Fig. 3. Each sash therefore has, at each side, two guide ribs which enter two 95 corresponding channels in the pocket or facing of the frame, the guide strips also constituting weather-guards, so that each sash, at each side, is provided with a double weather-guard whereby the admission of air 100 at the sides of the sashes, when the window is closed, is effectively prevented. Furthermore, it will be observed, this double weather-guarding of the sash is accomplished without the use of separate strips 105 and therefore with much less cost than would be involved in the provision of separate strips. Adjustment of the pocket may be effected by adjusting the screws *e*¹ or the screws *e*² or both, these screws being tapped 110

into the bracing *e* by which the pocket or facing is secured to the window frame. The bracing *e*, as will be observed, is preferably bent in substantially a double S-shape so 5 as to conform somewhat to the inner contour of the pocket or facing.

I claim as my invention:

1. In combination, a metal window frame having a vertical side bar formed with in- 10 turned flanges and a separable pocket or facing plate formed in one piece with two vertical channels and its edges turned in and lapped outwardly upon said inturned flanges to permit the pocket or facing plate 15 to be moved inward and forming guide-channels with said inturned flanges, and heavy metal bracings secured to the frame and to the facing plate.

2. In combination, a metal window frame 20 having a vertical side bar with inturned flanges and a separable pocket or facing plate formed in one piece with two vertical channels and with its edges turned inward and lapped outwardly on said vertical 25 flanges to permit the pocket or facing plate

to be moved inward and form guide channels with said flanges and metal sashes having each of its side members formed with two guide ribs to enter the corresponding channels in the face plate.

3. In combination, a metal window frame having a vertical side bar with inturned flanges and a separable pocket or facing plate formed in one piece with two vertical channels and with its edges turned inward 35 and lapped outwardly on said vertical flanges to form therewith guide channels and metal sashes having each of its side members formed with two guide ribs to enter the corresponding channels in the face 40 plate, and heavy metal bracing secured to the frame externally and internally with respect to the sashes and to the facing plate.

This specification signed and witnessed this 5th day of August A. D., 1913.

ALEXANDER FROMHOLD.
